WALL SUPPORT FOR TILING, BLOCKS, OR MONOLITHS

Thomas S. Whiteside, Pawtucket, R. I.

Application October 26, 1934, Serial No. 750,216

6 Claims. (Cl. 72—101)

This invention relates to certain new and useful improvements in wall support for tiling, blocks or monoliths.

In the laying of wall tile and the like, it has heretofore been the usual practice to lay the tile individually during the building of the wall which is a slow and tedious process and it is therefore the primary object of this invention to expedite such work by preforming the tile into a monolith and thereafter associating the tile monolith with a holder element previously anchored to studding or other part of a wall structure so that with the mounting of tile monoliths, the tiled wall is completely constructed.

A further object of the invention is to provide a novel form of holder for a tile or block of monolith with the holder formed of separable interlocking members with one member attached to a wall structure, such as to the vertical studding thereof while the other member of the two-part holder is attached to a metal lath or other support for concrete or cement into which the tile or blocks are set, the building of the tile monolith being accomplished as shop work and later transported to the wall structure for assembly of the interlocking members of the holder resulting in the completion of the tile or block wall.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a fragmentary front elevational view of a room wall in course of construction showing wall studding upon which the holders for the tile monoliths are mounted;

Figure 2 is a detail sectional view of two vertical studdings with one of the members of the two-part holder secured between the studding;

Figure 3 is a detail sectional view taken on line 3—3 of Figure 1, showing the interlocking connection between the two members of the holder;

Figure 4 is a fragmentary perspective view, partly in section of the holder member that is attached to the wall studding; and

Figure 5 is a perspective view of the holder member that is permanently attached to the tile monolith.

As distinguished from the individual laying of wall tile, such as the tiled wall of a kitchen or bath room of a house, or in any other connection, it is the object of the present invention to

preform the tiles into a monolith and permanently attach thereto one member of a two-part holder for the wall support of the tile monolith with the other member of the two-part holder attached to vertical studding or other appropriate element of the wall structure. The forming of the tile monolith may be accomplished as shop work and such monolith may be formed in advance of immediate use and be ready for wall or other mounting when required. As shown in Figure 1, the wall structure embodies vertical studding 10 upon which tile monoliths 11 are supported.

The holder for the tile monolith comprises a pair of separable interlocking members 12 and 13, the member 12 being attached to the studding 10, while the member 13 forms an integral part of the tile monolith 11. The member 12 of the two-part holder is of elongated form and embodies a front plate 14 having an angle flange 15 at each end provided with openings 16 to facilitate attachment thereof to adjacent uprights or studdings 10 at the inner sides thereof as shown in Figure 2 with the front plate 14 substantially in the plane of the forward edges of the studding. The member 12 has a rear wall 17 spaced from the front wall 14 that is formed by bending a metal sheet upon itself with the rear wall 17 of less depth than the front wall 14. A longitudinally extending bead 18 is formed in the rear wall 17 intermediate the upper and lower edges thereof and bulged outwardly of said rear wall 17.

The other member 13 of the two-part holder for the tile monolith is shown in detail in Figure 5 and comprises a front wall 19 of elongated formation having a series of openings 20 adjacent its lower longitudinal edge and said front wall 19 carries a rear wall 21 formed by bending the metal sheet upon itself with the rear wall 21 spaced from the front wall 19. The rear wall 21 is provided with a longitudinally extending bead 22 bulged outwardly thereof for cooperation with the bead 18 of the member 12 in a manner to be presently described.

It is intended that the tile monolith 11 be constructed as shop work and said monolith comprises the holder member 13 forming an integral part thereof and having a metal lath 22 or other cement support riveted as at 24 to the lower edge of the front wall 19 of the holder member 13 with the rivets passing through the openings 20 in said front wall. The connected holder member 13 and metal laths 23 are laid upon a flat support and concrete, cement or the like

25 is spread thereon to the desired depth and tiles 11a are mounted upon the cement coating 25 with the latter allowed to set with the tile permanently attached thereto. The monolith 5 then comprises the holder member 13, metal lath 23, cement 25 and tiles 11a. When it is desired to assemble a tile monolith upon a wall structure as shown in Figure 1, it being understood that the holder members 12 are first mounted in position upon the vertical studding or other members of the support, the holder member 13 has the lower edge of the rear wall 21 thereof placed over the upper edge of the front wall 14 of the holder member 12 and moved downwardly thereon with the bead 22 upon the holder member 13 pressed into interlocking engagement with the bead 18 on the rear wall 17 of the holder member 12, the coating beads 18 and 22 forming a separable interlocking connection between 10 the holder members and in turn the tile monolith 11 and the holder member 12. The tile monoliths may be constructed in different sizes and upon small room walls, a single monolith may be employed, whereas in larger constructions a series of tile monoliths may be used.

From the above detailed description of the invention, it is believed that the construction and operation thereof will at once be apparent and while there is herein shown and described 30 the preferred embodiment of the invention, it is nevertheless to be understood that minor changes may be made therein without departing from the spirit and scope of the invention as claimed.

35 I claim:—

1. A wall construction comprising a two-part separable holder, one part of the holder being attached to the wall and a tile monolith attached to the other part of the holder, and an interlocking connection between the two parts of the holder including resilient walls having interfitting protuberances.

2. A wall construction comprising a two-part separable holder, one part of the holder being attached to the wall and a tile monolith attached to the other part of the holder, and an interlocking connection between the two parts of the holder including a beaded wall on each holder part with the beads interfitting when the holder parts are assembled.

3. A wall construction comprising a two-part separable holder, one part of the holder being attached to the wall, a tile monolith attached to the other part of the holder, the tile monolith including a metal lath secured to the holder part, a cement binder upon the metal lath, and tiles secured to the cement binder.

4. A wall construction comprising a two-part separable holder, one part of the holder being attached to the wall, a tile monolith attached to the other part of the holder, an interlocking connection between the two parts of the holder, 20 the tile monolith including a metal lath secured to the holder part, a cement binder upon the metal lath, and tiles secured to the cement binder.

5. A wall construction comprising a two-part separable holder, one part of the holder being attached to the wall and a tile monolith attached to the other part of the holder, an interlocking connection between the two parts of the holder including a beaded wall on each holder part with the beads interfitting when the holder parts are 30 assembled, the tile monolith including a metal lath secured to the holder part, a cement binder upon the metal lath and tiles secured to the cement binder.

6. A wall construction comprising a two-part separable holder, one part of the holder being attached to the wall and a tile monolith attached to the other part of the holder, each holder part having front and rear walls and a longitudinal bead on each rear wall whereby the parts are 40 interlockingly connected when assembled.

THOMAS S. WHITESIDE.
